REFRIGERATION

Andrew A. Kucher, Dayton, Ohio, assignor, by
mesne assignments, to General Motors Cor-
poration, a corporation of Delaware

Application April 28, 1932, Serial No. 608,052
Renewed September 10, 1938

26 Claims. (Cl. 62—115)

This invention relates to refrigeration.

It is among the objects of this invention to provide a refrigerating apparatus of the continuously running compressor-condenser evaporator type, such as is described in my copending application Serial No. 599,239, filed March 16, 1932, to which reference is hereby made for a further understanding of this invention, with improved ice-making capacity.

10 It is a further object of this invention to provide such an apparatus with a readily accessible adjustment for selectively varying the refrigerating effect of the system on the object being cooled. Also it is an object of this invention to 15 render a refrigerating apparatus continuously or intermittently running type more adaptable to transportation for service or installation.

Further objects and advantages of the present invention will be apparent from the following 20 description, reference being had to the accompanying drawing, wherein a preferred form of the present invention is clearly shown.

In the drawings:

Fig. 1 is a vertical cross-sectional view of an 25 apparatus embodying features of this invention;

Fig. 2 is a partial horizontal cross-sectional view taken along the line 2—2 of Fig. 1;

Figs. 3 and 4 are diagrammatic and exaggerated views indicating varying ratios of liquid 30 refrigerant in the evaporator and condenser when the system operates under normal conditions when ice is not being made, and under abnormal, or ice making conditions;

Fig. 5 is a vertical cross-sectional view of a 35 portion of Fig. 1, taken along the line 5—5 thereof;

Fig. 6 is an enlarged horizontal cross-sectional view taken along the line 6—6 of Fig. 5;

Fig. 7 shows the compressor-condenser- 40 evaporator system removed from the cabinet and rendered compact for transportation;

Fig. 8 is a view showing the system removed 45 from the cabinet and rendered compact in another manner, and crated for transportation; and

Fig. 9 is a cross-sectional detail of one of the refrigerant lines, showing a protective covering to prevent sharp bends.

50 *Modification for increasing the ice producing capacity*

Sometimes it is desirable to increase the ice making capacity of the type of system described in my copending application above referred to, and for this purpose the construction may be

modified as shown in Figs. 1 and 2 and diagrammatically indicated in Figs. 3 and 4.

In this construction the evaporator 200 is provided with a relatively large liquid refrigerant reservoir in the ice-making zone capable of holding a large reserve supply of liquid refrigerant of such volume that, when it is transferred to the condenser, the effective condensing area of the condenser is materially reduced. When so constructed, the decreased effective condensing 10 area of the condenser materially increases the condensing pressures above normal operation pressure, and thus causes an increased flow of refrigerant into the evaporator through the restrictor. The refrigeration capacity of the system is thus temporarily increased by the increased refrigerant flow and provides a substantial 15 increase in the ice freezing capacity of the system.

As shown in Figs. 1 and 5, the evaporator 200 is provided with a relatively large liquid refrigerant reservoir, which may conveniently be formed by the ice tray shelves 201 and 202 which enclose the liquid refrigerant spaces 203 and 204 capable of containing a substantial amount of 25 liquid refrigerant. When this refrigerant is transferred to the condenser under abnormal, or ice-making conditions, the liquid refrigerant stands in the condenser a certain distance above the normal liquid refrigerant level therein and 30 preferably the liquid refrigerant capacities are so correlated in the system that the liquid refrigerant rises to the header 205 of the condenser 206 under abnormal, or ice-making, operation.

The operation of a system made with this increased ice freezing capacity is as follows: Under 35 normal operation when ice is not being made, the compressor 207 which runs continuously at a constant speed without stopping for cabinet temperature adjustments, in accordance with the disclosure in my copending application, compresses refrigerant and discharges it through the line 208 to the condenser 206. Under normal operation, the amount of refrigerant in the system is such that liquid refrigerant does not rise 40 substantially above the header or liquid refrigerant receiver 209. The liquid refrigerant then continues through the pipe 210 to the refrigerant expander 211. The expander 211 may be of the construction shown in my copending application, 45 or it may be modified as shown in Fig. 6 hereafter to be more fully described. The expanded refrigerant then passes through the pipe 212 to the liquid space 204. Thereafter it passes through the pipe 213 to the liquid space 203. 50 55

From thence it continues through the pipe 214 to the distributing channel 215 from whence it passes around the spot-welds 216 in the outer shell 221 of the evaporator in a manner similar 5 to the operation described in the said application and continues to the heat interchanger 217 where it cools the incoming unexpanded liquid refrigerant in pipe 210 which connects the condenser 206 with the expander 211, from thence 10 it continues through the pipe 218 to the compressor and repeats the cycle.

Under normal operation, when ice is not being frozen, the liquid refrigerant in the spaces 203 and 204, being insulated more or less from the 15 air currents in the food compartment 219 of the cabinet 220, does not evaporate materially beyond the requirements for removing the specific heat of the condenser liquid, and the construction is such that the unevaporated liquid stands 20 in a relatively quiescent condition in these reservoirs and is discharged or spills over into the distributing channel 215 of the air cooling outer shell 221 of the evaporator. Under normal conditions the refrigerant which is absorbing the heat leak into the cabinet is evaporated substantially only in the outer shell 221 and a certain quantity of reserve liquid refrigerant stands in the spaces 203 and 204 in readiness to be used for abnormal or ice-making conditions for increasing the capacity of the system. The quantity of refrigerant in the system is such that liquid refrigerant normally stands only in the receiver 209 of the condenser 206 as diagrammatically shown in Fig. 3. When the trays 222 and 223 are inserted into the evaporator with water to be frozen, and thus create an abnormal operating condition, a large quantity of heat is introduced into the liquid refrigerant in the spaces 203 and 204 and causes a large quantity 40 of liquid refrigerant to be evaporated. This quickly increases the back pressure in the evaporator, so that the compressor 201, because of its continuous operation, introduces a large quantity of refrigerant into the condenser 206. This 45 refrigerant is quickly condensed, so that an abnormally large quantity of liquid refrigerant is introduced into the condenser faster than it is normally discharged by the expander 211 into the evaporator 200. Under such abnormal conditions, the ratio of liquid refrigerant in the 50 evaporator and condenser is varied, the liquid refrigerant in the condenser 206 rising above the normal level in an amount sufficient to blanket the effective condensing area and thus increase the normal condensing pressures, as diagrammatically shown in Fig. 4. The header 205 is placed in the condenser at the proper height and is of sufficient capacity to prevent liquid refrigerant from rising in the condenser above 55 this point. The header 205 thus insures the proper ratio of blanketing in the condenser and removes the necessity of too closely measuring the amount of refrigerant introduced into the system. The abnormally high condenser pressures produced under ice-making conditions force an increased amount of liquid refrigerant through the expander 211, which in turn provides an increased amount of refrigerant to be 60 evaporated in the evaporator. Under these conditions the system operates at an increased capacity over the normal operation as described in my copending application. As the water turns into ice, the rate of evaporation of refrigerant due to the ice-making factor is reduced, and

gradually the system returns to its normal operation.

Temperature adjustments for individual requirements

When desired, means are provided whereby the user may vary the temperatures maintained by the system in the object being cooled. To this end, convenient means of varying the effective length of the expander is provided. For this purpose an expander, such as the expander 211, may be made of such cross-sectional area and length that for normal operation the refrigerant enters through the pipe 210, continues through the passage 230, is discharged through the passage 231 to the pipe 212 from whence it is discharged into the evaporator, this combined length and area being determined in accordance with my copending application. Supplemental passages 232, 233 and 234 may be provided which 20 tap the passage 230 at various points on one or both sides of passage 231. Any suitable means of establishing a refrigerant flow connection between any of the passages 231, 232, 233 or 234 with the passage 230 may be provided, and for 25 this purpose a vernier-like valve 235 may be used. This valve conveniently is in the form of a rod having transverse passages 236 to 239 inclusive so arranged that they connect the various passages 231 to 234 inclusive with the passage 230 and with the pipe 212, depending on the position of the valve 235 as is apparent from Fig. 6. The valve 235 may be provided with convenient means for manual adjustment. This may include a bellows 240 to prevent the flow 30 of refrigerant along the valve or rod 235. A spring 241 urges the valve 235 in one direction as shown in Fig. 6 and this force is counteracted by the manual adjustment device. This device includes the cam-like structure 242 secured to the valve 235 cooperating with the revolvable cam 243 having a ball and track engagement 244 with the front plate 245 of the evaporator 200. By turning the cam 243 to positions indicated by the pointer 246, various positions of the valve 235 are obtained which vary the effective length of the passage 230. By this means, the individual user of the system can select any one of several lengths of orifice which increase or decrease the capacity of the system and thus provide colder or warmer temperatures in the cabinet 220 or other object being cooled.

The calibration of the elongated orifice, in accordance with my copending application, is such that the flow through the passages 230 and 231 provides the normal cabinet temperature desired. When the user varies the length of the orifice by turning the cam 243, the effective length is varied slightly, but sufficiently to vary the temperature of the cabinet. Such adjustment maintains a substantially constant temperature with each of the points of adjustment, since the variations in length are relatively small with respect to the entire length of the orifice. Therefore it is possible for the user to select several different and substantially constant temperatures which will be maintained in the cabinet depending on the position or adjustment of the cam 243.

Servicing

This and similar systems may, if desired, be constructed so as to be adapted for "factory service". Under such conditions it is desirable to construct the compressor, condenser and evaporator as a unitary structure which may be re-

5 moved from the cabinet without disconnecting the refrigerant connections and may thus be transported to the factory or branch for repair. To this end the condenser 206 is shown as secured to a vertical side of the cabinet 220 by screws or the like 250 which are readily removed. The compressor and evaporator are mounted on a common base 251 which is supported on the cabinet independently of the condenser. The 10 base 251 may form at least part of one of the walls of the cabinet and preferably forms part of the top of the food compartment. The condenser is connected to the compressor and evaporator by flexible lines 208 and 210 so that 15 the system may be rendered more compact for transportation after it is removed from the cabinet. The condenser, together with the evaporator and compressor may be removed with the top 251 of the food compartment. This 20 unitary structure may be shipped in any convenient crate either by bending the pipes 208 and 210 so that the condenser assumes the position as shown in Fig. 7, or it may be placed alongside the condenser and evaporator so that 25 it may be shipped in a crate as shown in Fig. 8, and under these conditions, the lines 208 and 210 may have part of their outer surfaces protected by spirally wound wire 252 in order to protect the same from undue kinking during the 30 servicing operation.

The condenser may be provided with means for insuring that it is properly spaced from the wall of the building in which the apparatus is installed, so that an effective circulation of air over the condenser is obtained. Preferably such means are made integral with the condenser. The condenser is made of two metal sheets 260 and 261 welded together along the edges and spot-welded at intermediate points where one of the sheets is indented at 262. Sheets 260 extends beyond sheet 261 and is bent as at 263 to provide abutments which limit the extent to which the cabinet may be moved towards the wall 264 of the building, and thus insures proper air circulation on both sides of the flat air cooled portion of the condenser which lies between the abutments 263.

50 While the form of embodiment of the invention as herein disclosed, constitutes a preferred form, it is to be understood that other forms might be adopted, all coming within the scope of the claims which follow.

What is claimed is as follows:

55 1. A refrigerating apparatus consisting of a cabinet, a refrigerating system therefor of a capacity not substantially in excess of the maximum normal refrigeration requirements of said cabinet, said system comprising a compressor-condenser-evaporator refrigerating system in which the compressor runs continuously at constant speed during the entire period of refrigeration requirement without stopping for cabinet refrigeration temperature adjustments, and circulates refrigerant continuously throughout the entire system, a refrigerant expander of normally fixed dimensions between the condenser and evaporator of a size to vary the effective refrigerating area of the evaporator in response to refrigerant pressure in the evaporator in an amount sufficient to maintain the cabinet temperature within food preserving limits notwithstanding variations in the heat leakage through the walls into the cabinet, and means selectively to vary at least one dimension of said expander to produce a different refrigerating effect on the cabinet.

2. A refrigerating apparatus consisting of a cabinet, a refrigerating system therefor of a capacity not substantially in excess of the maximum normal refrigeration requirements of said cabinet, said system comprising a compressor-condenser-evaporator refrigerating system in which the compressor runs continuously at constant speed during the entire period of refrigeration requirement without stopping for cabinet refrigeration temperature adjustments, and circulates refrigerant continuously throughout the entire system, a refrigerant expander of normally fixed dimensions between the condenser and evaporator of a size to vary the refrigerant flow in response to the refrigerant pressures in the evaporator and condenser in an amount sufficient to maintain the cabinet temperature within food preserving limits notwithstanding variations in the heat leakage through the walls into the cabinet, and means selectively to vary at least one dimension of said expander to produce a different refrigerating effect on the cabinet.

3. A refrigerating apparatus comprising a household refrigerator cabinet having a food preserving space and an ice-making space, a compressor - condenser - evaporator refrigerator system assembled with said cabinet, said compressor operating continuously and circulating refrigerant continuously throughout the system and throughout the normal room temperature range without stopping for cabinet temperature adjustments, said evaporator having a refrigerant evaporating portion in thermal contact with said ice-making space and another evaporating portion in thermal contact with said food preserving space, an elongated orifice between said condenser and said evaporator having a length and cross-sectional area coordinated with the heat leak into the cabinet under varying room temperatures so that the evaporator maintains the cabinet temperature within food preserving limits and the ice-making space below 32° F. notwithstanding the continuous operation of the compressor and the variations in room temperature, and means to vary the length of said orifice the construction being such that the introduction of water to be frozen into said ice-making space causes an abnormal rise in condenser pressure. 40 45

4. A refrigerating apparatus comprising a household refrigerator cabinet having a food preserving space and an ice-making space, a compressor - condenser - evaporator refrigerator system assembled with said cabinet, said compressor operating continuously and circulating refrigerant continuously throughout the system and throughout the normal room temperature range without stopping for cabinet temperature adjustments, said condenser having an air cooled effective condensing area said evaporator having a refrigerant evaporating portion in thermal contact with said ice-making space and another evaporating portion in thermal contact with said food preserving space, an elongated orifice between said condenser and said evaporator having a length and cross-sectional area coordinated with the heat leak into the cabinet under varying room temperatures so that the evaporator maintains the cabinet temperature within food preserving limits and the ice-making space below 32° F. notwithstanding the continuous operation of the compressor and the variations in room temperature, the construction of the condenser and the charge of refrigerant being such that the introduction of water to be

frozen into said ice-making space causes an abnormal rise of liquid refrigerant in said condenser at the condenser area to reduce materially its effective condensing area.

5. A refrigerating apparatus comprising a household refrigerator cabinet having a food preserving space and an ice-making space, a compressor-condenser-evaporator refrigerator system assembled with said cabinet, said compressor operating continuously and circulating refrigerant continuously throughout the system and throughout the normal room temperature range without stopping for cabinet temperature adjustments, said evaporator having a refrigerant evaporating portion in thermal contact with said ice-making space and another evaporating portion in thermal contact with said food preserving space, an elongated orifice between said condenser and said evaporator having a length and cross-sectional area coordinated with the heat leak into the cabinet under varying room temperatures so that the evaporator maintains the cabinet temperature within food preserving limits and the ice-making space below 32° F. notwithstanding the continuous operation of the compressor and the variations in room temperature, the construction of said condenser being such that the introduction of water to be frozen into said ice-making space causes an abnormal rise of liquid refrigerant in said condenser to reduce materially its effective condensing area, said condenser having a reservoir intermediate its inlet and normal liquid level to limit the abnormal rise of liquid refrigerant.

6. A refrigerating apparatus consisting of a household refrigerator cabinet having a food preserving space and an ice-making space, a compressor-condenser-evaporator refrigerator system assembled with said cabinet, said compressor operating continuously and circulating refrigerant continuously at constant speed throughout the system and throughout the normal room temperature range without stopping for cabinet temperature adjustments, said evaporator having a relatively long refrigerant passage between its inlet and outlet in thermal contact with the ice-making space and means shielding said ice-making space from the food preserving space of the cabinet, a refrigerant expander having a normally fixed dimension between said condenser and the inlet of said evaporator to vary the effective refrigerating area and refrigerant temperature of said evaporator in an amount sufficient to maintain the cabinet temperature within food preserving limits and the ice-making space below 32° F., and expander adjustment means for selectively varying the expanding capacity of said expander.

7. A refrigerating apparatus comprising a domestic refrigerator cabinet having a food preserving space, a compressor-condenser-evaporator refrigerator system assembled with said cabinet, said compressor operating continuously and circulating refrigerant continuously throughout the system during the entire refrigeration requirements of the cabinet without stopping for cabinet temperature adjustments, an evaporator in said cabinet having an ice-making portion including a liquid refrigerant reservoir shielded from said food preserving space, and having a cooling portion in thermal contact with said food preserving space, and an elongated orifice between said condenser and said evaporator having a length and cross-sectional area coordinated with the heat leak into the cabinet under varying room temperatures so that it varies the

evaporator cooling capacity in an amount sufficient to maintain the cabinet food preserving space temperature within food preserving limits notwithstanding the continuous operation of the compressor and the variations in room temperature, the charge of refrigerant in said system being such that when liquid refrigerant is evaporated in said liquid refrigerant reservoir by water introduced in said ice-making portion, the effective condensing area in said condenser is blanketed by a rise in the normal condenser liquid level to increase the flow of refrigerant through said orifice. 5 10

8. A refrigerating apparatus comprising a domestic refrigerator cabinet having a food preserving space, a compressor-condenser-evaporator refrigerator system assembled with said cabinet, said compressor operating continuously and circulating refrigerant continuously throughout the system during the entire refrigeration requirements of the cabinet without stopping for cabinet temperature adjustments, an evaporator in said cabinet having an ice-making portion including a liquid refrigerant reservoir shielded from said food preserving space, and having a cooling portion in thermal contact with said food preserving space, and an elongated orifice between said condenser and said evaporator having a length and cross-sectional area coordinated with the heat leak into the cabinet under varying room temperatures so that it varies the evaporator cooling capacity in an amount sufficient to maintain the cabinet food preserving space temperature within food preserving limits notwithstanding the continuous operation of the compressor and the variations in room temperature, the charge of refrigerant in said system being such that when liquid refrigerant is evaporated in said liquid refrigerant reservoir by water introduced in said ice-making portion the effective condensing area in said condenser is blanketed by a rise in the normal condenser liquid level to increase the flow of refrigerant through said orifice, said condenser being provided with an intermediate reservoir to prevent a rise of liquid level in said condenser above said intermediate reservoir. 45

9. A refrigerating apparatus consisting of a cabinet, a compressor-condenser-evaporator refrigerating system therefor, said system including a continuously running compressor which circulates refrigerant throughout the entire system continuously at constant speed during the entire period of refrigeration requirement without stopping for cabinet refrigeration temperature adjustments, a normally fixed elongated orifice of a length dimension and cross-sectional area dimension sufficient to vary the evaporator capacity to maintain the cabinet temperature within food preserving limits notwithstanding variations in temperature of the air surrounding the cabinet, and means for selectively varying one of said dimensions of said orifice. 50 55 60 65

10. A refrigerating apparatus comprising a household refrigerator cabinet having a food preserving space and an ice-making space, a compressor-condenser-fixed restrictor-evaporator refrigerator system assembled with said cabinet, said compressor operating continuously and circulating refrigerant continuously throughout the system and throughout the normal room temperature range without stopping for cabinet temperature adjustments, said condenser having a liquid receiver and an effective condensing area above said receiver, an elongated orifice of a length and cross-sectional area sufficient for

- varying the capacity of the system throughout the normal room temperature range in an amount sufficient to produce the required quantity of ice and to maintain the cabinet within 5 the food preserving temperature zone, said condenser being of a construction and said evaporator having a normal liquid refrigerant content sufficient and effective to raise the condenser liquid refrigerant level to decrease the effective 10 condensing area and increase the condenser pressure in an amount to increase the normal capacity of the system upon the introduction of water to be frozen.
11. The method of maintaining an object to 15 be cooled at the desired temperature which comprises circulating refrigerant continuously throughout a compressor-condenser-evaporator refrigerating system in thermal contact with said object without stopping said compressor for object 20 temperature adjustments, expanding said refrigerant between said condenser and evaporator through an elongated orifice of a length and cross-sectional area sufficient for varying the capacity of the system throughout the normal 25 surface atmospheric temperature range to maintain said object at the desired temperature, and modifying the normal circulation of refrigerant in said system upon an abnormal refrigeration demand by abnormally varying the ratio 30 of liquid refrigerant in said evaporator and condenser to decrease the effective condensing area and to increase the condenser pressure and vary the normal flow of refrigerant through said orifice.
12. A refrigerating apparatus comprising a cabinet and a compressor-condenser-evaporator system unitarily assembled on said cabinet, said compressor and evaporator being mounted on a base removable from said cabinet, said condenser being removably secured to said cabinet by means other than said base, and flexible refrigerant connections from said condenser to said compressor and evaporator whereby said system may be removed from said cabinet without disconnecting the refrigerant flow connections and may be rendered compact for transportation.
13. A refrigerating apparatus comprising a cabinet and a compressor-condenser-evaporator system unitarily assembled on said cabinet, said compressor and evaporator being mounted on a base removable from said cabinet, and forming at least part of a wall of said cabinet, said condenser being removably secured to a vertical side of said cabinet by means other than said base, and flexible refrigerant connections from said condenser to said compressor and evaporator whereby said system may be removed from said cabinet without disconnecting the refrigerant flow connections and may be rendered compact for transportation.
14. A refrigerating apparatus comprising a cabinet and a refrigerating system assembled with said cabinet, said system including a condenser mounted on one of the vertical walls of the cabinet, said condenser comprising a flat vertical air-cooled portion formed of two metal sheets parallel with said vertical wall, one of said sheets having a projection formed by a portion of said sheet for limiting the movement of the cabinet toward a wall of the building in which it is installed to insure air circulating spaces on both sides of said air-cooled portion.
15. A refrigerating apparatus comprising a household refrigerator cabinet having a food preserving space and an ice-making space, a compressor-condenser-evaporator refrigerator system assembled with said cabinet, said evaporator having a refrigerant evaporating portion in thermal contact with said ice-making space and an evaporating portion in thermal contact with said food preserving space, an elongated orifice between said condenser and said evaporator having a length and cross-sectional area to maintain a flow of liquid into said orifice from said condenser under all normal room temperature compressor operating conditions, the construction being such that the introduction of water to be frozen into said ice-making space causes an abnormal rise of liquid refrigerant in said condenser to reduce materially its effective condensing area, and means to limit the rise of liquid in said condenser beyond a predetermined point.
16. A refrigerating apparatus comprising a household refrigerator cabinet having a food preserving space and an ice-making space, a compressor-condenser-evaporator refrigerator system assembled with said cabinet, said evaporator having a refrigerant evaporating portion in thermal contact with said ice-making space and an evaporating portion in thermal contact with said food preserving space, an elongated orifice between said condenser and said evaporator having a length and cross-sectional area to maintain a flow of liquid into said orifice from said condenser under all normal room temperature compressor operating conditions, the construction being such that the introduction of water to be frozen into said ice-making space causes an abnormal rise of liquid refrigerant in said condenser to reduce materially its effective condensing area, said condenser having a reservoir intermediate its inlet and normal liquid level to limit the abnormal rise of liquid refrigerant.
17. A refrigerating apparatus comprising a domestic refrigerator cabinet having a food preserving space, a compressor-condenser-evaporator refrigerator system assembled with said cabinet, an evaporator in said cabinet having an ice-making portion including a liquid refrigerant reservoir, and having a cooling portion in thermal contact with said food preserving space, and an elongated orifice between said condenser and said evaporator having a length and cross-sectional area to maintain a flow of liquid into said orifice from said condenser under all normal room temperature, compressor operating conditions, the charge of refrigerant in said system being such that when liquid refrigerant is evaporated in said liquid refrigerant reservoir by water introduced in said ice-making portion, the effective condensing area in said condenser is blanketed by a rise in the normal condenser liquid level to increase the flow of refrigerant through said orifice, said condenser being provided with an intermediate reservoir to prevent a rise of liquid level in said condenser above said intermediate reservoir.
18. A refrigerating apparatus comprising a household refrigerator cabinet having a food preserving space and an ice-making space, a compressor-condenser-fixed restrictor-evaporator refrigerator system assembled with said cabinet, said compressor operating continuously and circulating refrigerant continuously throughout the system and throughout the normal room temperature range without stopping for cabinet temperature adjustments, said condenser having an air cooled effective condensing area, an elongated orifice between said condenser and evaporator, the length and cross-sectional area of said orifice, the refrigerant content and construction of said condenser and evaporator being so arranged that

upon the introduction of water to be frozen into said ice-making space, the effective condensing area in said condenser is substantially blanketed by a rise in the normal condenser liquid level to increase the flow of refrigerant through said orifice.

19. A refrigerating apparatus comprising a household refrigerator cabinet having a food preserving space and an ice-making space, a compressor-condenser-evaporator refrigerator system assembled with said cabinet, said compressor operating continuously and circulating refrigerant continuously throughout the system and throughout the normal room temperature range without stopping for cabinet temperature adjustments, an elongated orifice between said condenser and evaporator, the length and cross-sectional area of said orifice, the refrigerant content and construction of said condenser and evaporator being so arranged that upon the introduction of water to be frozen into said ice-making space, the effective condensing area in said condenser is blanketed by a rise in the normal condenser liquid level to increase the flow of refrigerant through said orifice, said condenser being provided with an intermediate reservoir of a capacity sufficient to prevent a rise of liquid level in said condenser above said intermediate reservoir.

30. A refrigerating apparatus comprising a cabinet and a refrigerating system assembled with said cabinet, said system including a condenser mounted on one of the vertical walls of the cabinet, said condenser comprising a flat vertical air-cooled portion formed of two metal sheets parallel with said vertical wall, means along the edges of said condenser enclosing the space between said condenser and cabinet wall to form a flue, and means along the edges of said condenser adapted to enclose the space between said condenser and a wall of the building in which it is installed to form a second flue.

21. A refrigerating apparatus comprising a compressor-condenser and evaporator, said condenser comprising a relatively elongated flat surface and having a normal refrigerant reservoir at the bottom and a second liquid receiver above said first named receiver for limiting the rise of liquid refrigerant in said condenser and a charge of refrigerant in said system sufficient for the liquid refrigerant to rise above said first named receiver at times during the operation of said system, but insufficient to rise above said second receiver.

55. The method of refrigerating a food preserving space and a freezing space which comprises expanding refrigerant through a fixed elongated orifice, discharging the refrigerant so expanded into a reservoir in said freezing space and shielded from the circulation of air in said food space, normally maintaining a body of liquid refrigerant in said reservoir, overflowing liquid refrigerant from said reservoir into a food storage compartment cooling chamber, reliquefying refrigerant thus evaporated, returning the reliquefied refrigerant to be re-expanded, and pre-cooling the reliquefied refrigerant being so returned by thermal exchange with evaporated refrigerant.

70. A refrigerating apparatus comprising a household refrigerator cabinet having a food preserving space and an ice-making space, a closed

compressor - condenser - evaporator refrigerator system assembled with said cabinet, said evaporator having a refrigerant evaporating portion in thermal contact with said ice-making space and an evaporating portion in thermal contact with said food preserving space, an elongated orifice between said condenser and said evaporator having a length and cross-sectional area to maintain a flow of liquid into said orifice from said condenser under all normal room temperature compressor operating conditions, the construction being such that the introduction of water to be frozen into said ice-making space causes an abnormal rise of liquid refrigerant in said condenser to reduce materially its effective condensing area, 15 said condenser having a reservoir intermediate its inlet and normal liquid level to limit the abnormal rise of liquid refrigerant.

24. A refrigerating apparatus comprising a domestic refrigerator cabinet having a food preserving space, a closed compressor-condenser-evaporator refrigerator system assembled with said cabinet, an evaporator in said cabinet having an ice-making portion including a liquid refrigerant reservoir, and having a cooling portion 20 in thermal contact with said food preserving space, and an elongated orifice between said condenser and said evaporator having a length and cross-sectional area to maintain a flow of liquid into said orifice from said condenser under all 25 normal room temperature, compressor operating conditions, the charge of refrigerant in said system being such that when liquid refrigerant is evaporated in said liquid refrigerant reservoir by water introduced in said ice-making portion, the 30 effective condensing area in said condenser is blanketed by a rise in the normal condenser liquid level to increase the flow of refrigerant through said orifice, said condenser being provided with an intermediate reservoir to prevent a rise of 40 liquid level in said condenser above said intermediate reservoir.

25. A refrigerating apparatus comprising a compressor-condenser and evaporator, said condenser comprising a relatively elongated passageway and having a normal liquid refrigerant discharge at the bottom and a liquid receiver above said discharge and intermediate the length of said passageway for limiting the rise of liquid refrigerant in said condenser, and a charge of refrigerant in said system sufficient for liquid refrigerant to rise above said discharge opening at 45 times during the operation of said system, but insufficient to rise above said receiver.

26. In a compressor-condenser-expander type 55 refrigerator, the method of maintaining a substantially constant temperature in a cabinet during changes in temperature of the environment air about the cabinet, which method consists in circulating refrigerant through an evaporator 60 which cools the interior of the cabinet and through a condenser which is subject to the said environment air, increasing and decreasing the contact surface between liquid refrigerant and the evaporator in accordance with increasing and decreasing demands, respectively, for refrigeration on the evaporator and increasing and decreasing the contact surface between the condenser and the gaseous refrigerant therein in accordance with increasing and decreasing demand, respectively, for refrigeration on the evaporator.

ANDREW A. KUCHER.
